ROLLER SHOULDER BIT

Filed Aug. 1, 1935

FIG. 1.

FIG. 2.

UNITED STATES PATENT OFFICE

2,080,117

ROLLER SHOULDER BIT

Charles A. Dean, Bakersfield, Calif.

Application August 1, 1935, Serial No. 34,186

10 Claims. (Cl. 255—71)

This invention pertains to drills for earth boring, and particularly to improvements in drill bits of roller cutter type for straightening deflected bore holes.

5 An object of this invention is to provide an improved bit to straighten bore holes in hard rock structure as well as in soft formation. Another object is to provide an assembly of roller cutters which as a whole is free-cutting and in which 10 cross-drag and wear are minimized; and further in which the working stresses are balanced so that it is feasible to mount the cutters on roller or other low friction bearings. An important purpose is to provide a bit that effects relatively rapid 15 initial penetration of a deflected side wall, followed by progressively increasing side thrust toward the new cut so that the bit will tend to "dig itself in" to the new wall.

A further object is to obtain improved arrangement and mounting of cutters so as to steady a 20 drill in operation and minimize deflection of an established bore. Other objects will appear with further description herein of preferred embodiments of the present invention taken in connection with the accompanying drawing. The invention comprises features of construction, combinations of elements and arrangements of parts which will be exemplified in the constructions hereinafter described and of which the scope of 25 application will be indicated in the appended claims.

In the drawing, which illustrates one preferred embodiment of this invention, Fig. 1 is a bottom or inverted plan view of the drill bit and roller cutter assembly; Fig. 2 is an elevation of the bit with cross-section through conoidal cross-roller cutters of the bit; and Fig. 3 represents an elevation, partly in vertical section, of one of the longitudinal cutters of the bit, viewed at a right angle 30 to Fig. 2 along the plane 3—3.

40 This invention advantageously embodies a bit-head in which are combined cross-roller cutters of conoidal form, preferably, having upwardly and inwardly inclined cutting surfaces, and longitudinal roller cutters having tangentially inclined side cutting surfaces and having bottom-cutting teeth adapted to effect a leading cut into part of the bottom formation below the cross-roller cutters. This combination penetrates initially into a deflected wall in a wedge-like arrangement of cutting teeth and then advances with increasing cutting effect and side pull as the inclined longitudinal roller cutter is rotated against the bottom 45 of the new cut. The rollers preferably are disposed symmetrically in the bit to promote de-

velopment and maintenance of a straight bore hole.

5 Referring more particularly to the drawing, the bit-head comprises a shank 1 adapted for engagement with the usual rotary drill stem. The shank terminates in downwardly projecting arms 2 and 3 adapted to carry roller cutters. These cutters comprise conoidal cross-roller cutter 4 and cylindrical longitudinal roller cutter 5. Longitudinal cutters 5 contain bottom-cutting teeth 11. The cross-roller cutters and the cylindrical longitudinal roller cutters are adapted to ream some portion of the side wall, but the cross-cutter 4 is adapted to function as leading cutter at the bottom edge and lower part of the side or periphery. 10 as illustrated by the cut shown in Fig. 3, while the cylindrical cutter 5 is adapted to function as leading cutter at an inner portion of the bottom after a new cut has been initiated. This arrangement 15 facilitates initial penetration into the side of a 20 deflected bore.

As shown in Fig. 2, cross-roller cutter 4 is mounted with roller-bearings 6 on spindle 7 and is locked thereto by screw 14. Spindle 7 projects inwardly from arm 2 and may be horizontal or 25 may be inclined. The shape of roller 4 preferably is frusto-conical with inwardly and upwardly inclined bottom-cutting teeth 8. The base of roller 4 faces outwardly of the bit, and is provided with teeth 9 adapted to operate outwardly of the arms 30 2 and 3. Preferably this toothed portion 9 of the base of cutter 4 intersects bottom teeth 8 at an acute angle, and the cutter 4 is mounted so that this edge of intersection between teeth 8 and 9 35 constitutes a wedge-like cutting element at the periphery of the bore. This edge is to constitute the leading contact with the bore wall, as shown in Fig. 2 and shown also by the cut in Fig. 3. Teeth 9 preferably cut the side of the bore substantially vertical, while teeth 8 in combination 40 therewith tend to form a recess or a trough at the bottom edge, as illustrated in Fig. 3. Thus when the drill is lowered into a deflected bore hole and is rotated, cross-roller 4 tends readily to embed 45 itself in the lower wall, such as wall 10, and start a vertical bore. As a shelf is cut into the deflected side, and the cutters penetrate further, there is continual side thrust to work the drill into the new bore. The bottom cutting teeth may be notched 50 to augment the side thrust.

55 The rotating drill penetrates the deflected wall by continued chipping action, effected initially by teeth 8 and 9 of the conoidal cross-rollers 4, and subsequently also by the bottom teeth 11 on longitudinal rollers 5. Low friction mounting of the 55

roller cutters 4 and 5 from arms 2 and 3 respectively, such as with ball bearings 6 of cutter 4, tends to promote a multiplicity of chipping cuts rather than a dragging action. As the bit is rotated in clockwise direction, the individual teeth 5 8 and 9 of cross-rollers 4 are brought into action in opposite direction. These cutting teeth build up in the bore wall the shoulder or shelf having an upward slope into which the cross-rollers 10 gradually settle.

As the conoidal cross-rollers 4 sink into the deflected wall, the vertical edges of longitudinal roller cutters 5 take up a reaming action along the upper side wall of the new cut. Cutter 5, as 15 shown, is inclined tangentially with its top about 20° preferably in a rearward direction from top to bottom having regard to the direction of rotation. Thus cutter 5 is given a twist in its reaming cuts. Also by this inclination of roller 5 its bottom cutter edges 11 descend to a lowermost point centrally of their forward edge. This is illustrated in Figs. 2 and 3. In Fig. 3 a vertical section through this cutter 5 converges at tooth 12. The cutting elements of cutter 5 at the peripheral edge of the new drill hole are preferably 20 above the corresponding peripheral cut of the conoidal cross-rollers 4. Thus, as the longitudinal roller cutter 5 comes into action to cut the bottom, the bottom conformation of the bore becomes that of an upward and inward slope containing an arcute or dished cut, deeper toward 25 the center of the bore, as illustrated in Fig. 3.

The inclination and position of longitudinal cutter 5 serve to introduce this cutter gradually 30 into the sloped bottom that is formed by conical cutter 4. The bottom-cutting teeth of the longitudinal cutter 5 effect a leading cut into an inner part of the bottom formation below the cross-roller cutters 8, and in effect thus become 35 driven cutters, but maximum penetration and cutting action of cutter 5 in this sloped bottom is thus attained gradually after the conoidal cutters 4 have initiated a cut in the deflected side wall. The maximum bottom-cutting action of 40 cutter 5 occurs at the inner side of its individual axis, as illustrated in Fig. 3. Cutting resistance on the bottom of this longitudinal cutter, thus predominant at its inner periphery, rotates cutter 5 on its individual axis as the drill rotates, 45 and thus accelerates the chipping action of this longitudinal cutter both on the bottom and on the side wall. As a result partly of the upward inclination of the new bottom cut toward the center of the bit, combined with the delayed and 50 gradual introduction of the longitudinal cutter into the cut, the bit rather than being forced away from the cut is gradually drawn into the new shelf. After the bit has progressed into the deflected wall to a point beyond the center of 55 the bit, the conformation of the cut is symmetrical and is of counterbalancing or stabilizing effect on both the bottom and sides of the bit. This facilitates the use of low friction bearings and freedom of rotation of the individual cutters. Consequently, as illustrated in the drawing, the cutters tend to chip into the cleared portion of a cut. The conoidal cutters tend to rotate counter to the rotation of the bit-head while the cylindrical longitudinal cutters by the preponderance of thrust at the inner portion of the bottom tend to rotate with the bit-head. Thus 60 there results a variety of complementary chipping cuts over the surfaces of the new bore hole.

In accordance with the patent statutes, I have 65 described what I now regard as the preferred 70

embodiment of this invention, and explained the principles thereof but within the terms of the appended claims various modifications and adaptations of this invention may now become apparent to those skilled in the art.

What is claimed is:

1. A roller bit for earth drilling, comprising a head having in combination a cross-roller cutter mounted therein with bottom-cutting teeth as a whole inclined upwardly and inwardly and extending substantially to the axis of the head, and a roller-cutter mounted therein for rotation about an axis longitudinal of the bit and having bottom-cutting teeth adapted to effect a leading cut into the upwardly and inwardly inclined bottom formation left below the cut of the said upwardly inclined cross-roller teeth.

2. A roller bit for earth drilling, comprising a head having in combination a cross-roller cutter mounted therein with bottom-cutting teeth as a whole inclined upwardly and inwardly and extending substantially to the axis of the head, and a roller-cutter mounted therein having bottom-cutting teeth adapted to effect a leading cut into the upwardly and inwardly inclined bottom formation left below the cut of the said upwardly inclined cross-roller teeth.

3. A roller bit for earth drilling, comprising a head having in combination a conoidal cross-roller cutter mounted therein with bottom-cutting teeth as a whole inclined upwardly and inwardly and adapted to effect a peripheral cut and to extend therefrom substantially to the axis of the head, and a cylindrical roller-cutter mounted therein with its axis longitudinal of the bit and with its upper end forwardly inclined in the direction of rotation of the drill and having bottom-cutting teeth adapted to effect a leading cut into the upwardly and inwardly inclined bottom formation left below the cut of the said upwardly inclined cross-roller teeth.

4. A roller bit for earth drilling, comprising a head having in combination a conoidal cross-roller mounted therein with bottom-cutting teeth as a whole inclined upwardly and inwardly and adapted to effect a peripheral cut and to extend therefrom substantially to the axis of the head, and a cylindrical roller-cutter mounted therein with its axis longitudinal of the bit and with its upper end forwardly inclined substantially 20° in the direction of rotation of the drill and having bottom-cutting teeth adapted to effect a leading cut into the upwardly and inwardly inclined bottom formation left below the cut of the said upwardly inclined cross-roller teeth.

5. A roller bit for earth drilling, comprising a head having in combination a conoidal cross-roller cutter mounted therein with bottom-cutting teeth as a whole inclined upwardly and inwardly and having a base containing wall-cutting teeth making an acute angle with the said bottom-cutting teeth, and a cylindrical roller-cutter mounted therein with its axis longitudinal of the bit and its upper end forwardly inclined in the direction of rotation of the drill, the cylindrical roller having bottom-cutting teeth adapted to effect a leading cut into the upwardly and inwardly inclined bottom formation left below the cut of the said conoidal cross-roller bottom-cutter, and having longitudinal teeth adapted to ream the side wall above the area contacted by the side-cutting teeth of the conoidal cross-roller.

6. A roller bit for earth drilling, comprising a head having in combination a conoidal cross-

- 5 roller cutter mounted therein with bottom-cutting teeth as a whole inclined upwardly and inwardly and adapted to effect a peripheral cut and to extend therefrom substantially to the axis of the head and with a base containing side-wall cutting teeth intersecting the bottom-cutting teeth at an acute angle to form a wedge-like peripheral cutting element, and a cylindrical roller-cutter mounted therein with its axis longitudinal 10 of the bit and its upper end forwardly inclined in the direction of rotation of the drill, the cylindrical roller having bottom-cutting teeth adapted to effect a leading cut into the upwardly and inwardly inclined bottom formation left below the 15 cut of the said conoidal cross-roller bottom-cutter, and having longitudinal teeth adapted to ream the side wall above the area contacted by the side-cutting teeth of the conoidal cross-roller.
- 20 7. A roller bit for earth drilling comprising a head having in combination a conoidal cross-roller mounted therein with bottom-cutting teeth as a whole inclined upwardly and inwardly and extending from the periphery substantially to the axis of the head, and a cylindrical roller-cutter mounted therein with its axis longitudinal 25 of the bit, and having bottom-cutting teeth adapted to effect a leading cut into the upwardly and inwardly inclined bottom formation left below the cut of the said upwardly inclined cross-roller teeth inwardly and above the periphery of the cut of the conoidal cross-roller, the conoidal cross-roller and the cylindrical longitudinal roller being mounted on low friction bearings.
- 30 8. A roller bit for earth drilling, comprising a head having in combination a conoidal cross-roller mounted therein, with bottom-cutting teeth as a whole inclined upwardly and inwardly and extending from the periphery substantially to the 35 axis of the head, and a cylindrical roller-cutter mounted therein with its axis longitudinal of the bit and from top to bottom rearwardly inclined in the direction of rotation of the bit, and hav-

ing bottom-cutting teeth adapted to effect a leading cut into the upwardly and inwardly inclined bottom formation left below the cut of the said conoidal cross-roller cutter, the bottom cutters of the conoidal cross-rollers at the outer peripheral edge of their cut being adapted to effect a leading cut below the corresponding outer edge of the cylindrical longitudinal roller-cutters.

9. A roller bit for earth drilling, comprising a head having a conoidal cross-roller cutter mounted therein with bottom cutting teeth as a whole inclined upwardly and inwardly and with a base extended outwardly to clear the drill head, said base containing side wall-cutting teeth intersecting said bottom-cutting teeth at an acute angle to 15 form a wedge-like peripheral cutting element adapted to facilitate penetration of a deflected bore wall and a roller cutter mounted in the head to effect a leading cut in the bottom formation above and inwardly of the peripheral cut of said 20 acute-angled cutters.

10. A roller bit for earth drilling, comprising a head having in combination a conoidal cross-roller cutter mounted therein with bottom-cutting teeth as a whole inclined upwardly and inwardly and extending substantially to the axis of the head and with a base extended outwardly to clear the drill head, said base containing side wall-cutting teeth intersecting said bottom-cutting teeth at an acute angle to 25 form a wedge-like peripheral cutting element adapted to facilitate penetration of a deflected bore wall and disposed to effect a leading cut into the side of a deflected bore wall, the bithead having therein also a roller-cutter mounted for rotation about an axis generally longitudinal of the bit and containing bottom-cutting elements adapted to 30 effect a leading cut into the upwardly and inwardly inclined bottom formation left below the cut of the said conoidal cross-roller cutter.

CHARLES A. DEAN.
